PROPELLER

Anton Rober, Milwaukee, Wis.

Application September 3, 1940, Serial No. 355,267

1 Claim. (Cl. 170—172)

My invention relates to new and useful improvements in airplane propellers.

An important object of my invention is to provide an airplane propeller that has provision for the passage of a fluid medium longitudinally therethrough. The said propeller being power-driven and the centrifugal force created thereby acting as a means for drawing atmospheric air therethrough.

Another object of my invention is the provision of a propeller of the above-mentioned character wherein the outer outlet ends of the internal air passages are uniquely shaped to utilize the discharging air in a manner whereby the blades of the propeller may better obtain traction against the air through which they are moving.

Still another object of my invention is the provision of a propeller of the above-mentioned character that is simple in its construction and that is efficient and efficacious in the performance of its duties.

Other objects and advantages of my invention, will be apparent during the course of the following description.

In the drawings, forming a part of this specification, and wherein like numerals are employed to designate like parts throughout the same,

Figure 1 is a top plan view of a propeller assembly embodying my invention,

Figure 2 is a front elevation thereof,

Figure 3 is a fragmentary rear elevation illustrating the construction of the hub and showing the association of the shanks of the propeller blades therewith,

Figure 4 is a vertical sectional view taken on the line 4—4 of Figure 3,

Figure 5 is a fragmentary transverse sectional view taken on the line 5—5 of Figure 3,

Figure 6 is a transverse sectional view taken on the line 6—6 of Figure 7 and illustrating a propeller blade constructed in accordance with the present invention,

Figure 6—a is a transverse sectional view showing a modification of Figure 6,

Figure 7 is a longitudinal sectional view of my propeller blade taken on the line 7—7 of Figure 6,

Figure 8 is a plan view of the locking disk adapted to hold the blades of the propeller in fixed association with the hub,

Figure 9 is a fragmentary perspective view further illustrating the association of the propeller shanks with the hub,

Figure 10 is a transverse sectional view of a modified form of my propeller blade,

Figure 11 is a fragmentary bottom plan view of another modification of my propeller blade,

Figure 12 is a transverse sectional view taken on the line 12—12 of Figure 11, and

Figure 13 is a transverse sectional view of a modified form of the propeller shank.

In the accompanying drawings, wherein for the purpose of illustration is shown a preferred embodiment of my invention, the numeral 15 designates the power-driven crankshaft of an internal combustion engine of a type commonly used in airplane manufacture. One end of the crankshaft extends through the crankcase and a propeller 16 is fixedly mounted thereon.

My invention concerns itself principally with the shape and construction of the propeller carried by the shaft 15, which propeller includes a central hub portion 17 and radially extending blades 18. The blades are here illustrated as being two in number and as being disposed in diametrically opposed relation with each other; however, it is to be understood that any number of blades desired may be used and that the present number is shown merely for the purpose of illustrating the invention.

The hub comprises a base ring casting 19 and a cap 20 which are detachably connected to each other in a manner whereby the outside surfaces thereof join smoothly to provide an essentially conical-shaped unit. The casting comprises an outer annular shell 21 and a central bearing 22 connected by the radially extending bifurcations 23 and 24. The outer end of each of the bifurcations terminates within the shell so that the internally splined sleeves 25 and 26 formed at their ends may receive the externally splined butt ends of the propeller shanks. As shown at Figure 3, each of the sleeves 25 is disposed to project through the exterior portion of the shell casting 19 so that the bores of the sleeves extend tangentially through the casting. The inner sleeve 26 of each pair of sleeves aligns with the outer sleeve to radially position the longitudinal axis of its respective propeller blade in the manner illustrated in Figure 2. The bearing 22 is splined to the extending end of the crankshaft 15 the tip of which shaft is screw-threaded, as at 27, to receive the locking nut 28. The outer end of the bearing is flared, as at 29, to provide a seat for the tapered inner end 30 of the locking nut and a cotter key 31, or the like, extends through aligning passages in the shaft and nut to prevent the nut from being inadvertently unthreaded from the crankshaft. Obviously, tightening of the nut upon the threaded end of the shaft

will cause the tapered inner end thereof to press snugly against the seat 29 in a manner to hold the bearing fixedly and permanently attached to the shaft.

The base of the hub cap 20 is provided with an inturned flange 32 which snugly abuts the beaded edge 33 of the shell 18. Spring clips 34 are mounted at circumferentially spaced intervals around the inner surface of the cap and the outer ends thereof extend beyond the flange 32 to resiliently engage the beaded edge of the hub in a manner to hold the cap generally fixedly but detachably associated with the casting.

Each of the propeller blades is identical in its construction and each is identically associated or connected to the hub. A detailed description of but one of the blades will, therefore, be given.

The blade 16 is provided with an elongated shank 35 the inner end 36 of which is tapered and received within the sleeves 25 and 26 and the outer end of which is flattened, as at 37. The inner tapered end 36 extends to substantially the rearward face 38 of the sleeve 26 and is fixedly held therein by means of the locking disk 39. The disk is provided with a circumferential wedge-shaped portion 40 extending from one side thereof which fits within the flared recess 41 in the rearward side of the sleeve. The inner periphery of the disk is formed at right-angularly disposed diametrically opposed sides thereof with spaced pairs of lugs 42 which extend at opposite sides of the openings 43 in the end of the propeller shank. The bolts 44 pass between the pairs of tabs and into the openings 43 and tightening of the bolts will operate to pull the tapered end of the shank into pressed engagement with the sleeves.

The flattened end portion 37 of the blade comprises an integral part of the shank and in the form thereof illustrated generally in Figures 1 to 9, and specifically in Figures 6, 6-a and 7 it comprises three spaced parallel fins 45, 46 and 47. The outer ends of the fins are closed by a vertical wall 48 to provide elongated slots or passages 49 which extend the full length of the blade and open through the leading edge 50 and trailing edge 51 thereof. The hub cap 20 is provided with a plurality of circumferentially spaced perforations 52 and the propeller shank is provided with a longitudinally extending passage 53, which passage discharges air entering through the perforations into the passages 55, 54 and 55 in the fins 45, 46 and 47. From the passages within the fins the air is discharged into the passages 49 intermediate the fins through a plurality of outlet ports 56 adjacent the leading edges thereof. The outlet ports 56 in the two lowermost fins 46 and 47 open through the upper surfaces thereof and into the passages 49, whereby air entering the said last-mentioned passages will traverse the same for substantially their entire width. The outlet ports in the uppermost fin 45 open through the bottom surface thereof and into the uppermost passage 49 for reasons presently to be made apparent.

As best illustrated in Figure 6, the leading edges of the fins are beveled, as at 57, and the trailing edges thereof are beveled, as at 58. In addition to the beveled formation 58, the trailing edge of each of the fins is bent angularly downwardly to provide striking surfaces 59 against which the air traversing the passages 49 will be impinged. The angularly bent rearward edges of the fins may be either plane or curved, the plane construction being illustrated in Figure 6

and the curved construction in Figure 6-a. Air traversing the upper passage 49 will be impinged against the obliquely disposed trailing edge of the upper fin 45 and air traversing the lower passage 49 will be impinged against the obliquely disposed striking face of the fin 46. If desired, suitable supporting braces 60 may be disposed between the fins at spaced intervals throughout the length of the blade to support and strengthen the same.

When the propeller is being rapidly rotated the air in advance of the propeller is drawn therein and, by reason of the unique shape of the propeller blades, is hurled rearwardly thereof at a greatly accelerated velocity. This unique situation causes a condition of reduced atmospheric pressure to exist slightly in front of the blades and a condition of increased atmospheric pressure to exist rearwardly thereof. The utility of a propeller depends to no small extent on the traction which it may obtain on the air in that the propeller literally screws itself through the air. The present arrangement, therefore, contemplates a propeller construction adapted to increase the traction which the blades of the propeller may obtain. As hereinbefore described, rotation of the propeller will cause air to pass through the slots 49 between the fins at the ends of the blades. The air traversing the slots will flow by the outlet ports 56 and tend to pull or exhaust the air from the passages 53, 54 and 55. The semi-exhausted condition of these passages will cause air to be sucked into the perforated propeller hub and along the shank and fin passages, which last-mentioned flow is discharged through the ports to augment the air already flowing therethrough. The increased pressure against the oblique striking faces 59 at the trailing edge of the fins will give the blades greater tractive force and will materially increase the efficiency of the propeller.

Each of the blades is preferably inclined from the horizontal at substantially the angle illustrated in Figure 6; however, this angle may be readily adjusted to suit the exigencies of the particular situation. The periphery of the shank 35 adjacent the outwardly extending end of the sleeve 25 is provided with circumferentially spaced marks 61 which cooperate with the arrow 62 on the edge of the sleeve to indicate the relative angular position of the fins at the end of the blade. If the bolts 44 are disengaged from the butt ends of the propeller shanks, the said shanks may be removed from the sleeves and reinserted at the desired angle, the angle being accurately ascertained by the particular mark 61 in register with the arrow 62. Reinsertion of the bolts 44 will then force the annular wedge 42 of the disk into the recess 41 to thereafter efficaciously hold the shank against longitudinal displacement.

It is to be understood that the number of fins which may be used is not restricted to any particular number and that three fins are illustrated in Figures 1 to 9 merely for the purpose of illustration. Figure 10 shows a propeller blade construction which embodies two fins 63 and 64. The outer ends of the fins are closed in the manner described for the preceding form and the slot or passage 65 opens through the leading and trailing edges of the blade. The construction of the blades and the formation of the fins is substantially identical with the form hereinbefore described. Both of the fins 63 and 64 are provided with longitudinal passages 66.

The passages 63 communicate with the longitudinal passage of the shank to deliver air through the outlet port 67 and into the passage 68 intermediate the fins in the same manner hereinabove described for the first form of the invention. The further construction and mode of operation of this form of the invention is so similar to the form hereinabove described that no further explanation is thought to be necessary.

Figures 11 and 12 illustrate a construction wherein only one fin 68 is required. The fin is integrally connected with the distal end of the shank and the leading edge thereof is beveled, as at 69, and the trailing edge thereof is beveled, as at 70. The trailing edge of the fin is similarly bent angularly downwardly to provide a striking surface 72 against which air is impinged in the manner hereinbefore described. The fin is provided with a longitudinally extending passage 73 and the bottom face 71 of the fin is provided at spaced intervals along its length with an outlet port. The sides of the ports confronting the trailing edge of the fin are bent inwardly to provide the tabs 74 which extend slightly into the passage 73. The air drawn from the shank passage and into the passage 73 will be directed by the concave outer surfaces of the tabs along the face 71 of the fin and against the striking surface of the trailing edge. It is preferred that all of the ports which open through the bottom faces of the fins be formed in the manner first described and as illustrated in the drawings.

Figure 13 is a cross-sectional view of a modification of the propeller shank. The internal passage 53 thereof is divided by right angularly disposed supporting partition walls 76 which

substantially increase the strength and durability of the blade. The outer ends of the subpassages 76 formed by the partition walls may open into a common chamber for discharging the air into the hollow fins or if a plurality of the fins are used, certain of the fins may be individually connected to corresponding subpassages.

It is to be understood that the form of my invention, herewith shown and described, is to be taken as a preferred example of the same, and that various changes in the size, shape and arrangement of parts may be resorted to without departing from the spirit of my invention, or scope of the appended claim.

Having thus described my invention, I claim:
A propeller assembly comprising a hollow perforated hub, and radially extending blades having tubular shank portions connected to and communicating with the hub and blades provided at the distal ends of the shanks, which blades comprise spaced parallel fins extending in or parallel to a plane containing the blades so that the passages therebetween extend the full length of the blade and open through both the leading and trailing edges thereof, each of the fins being angularly offset at its trailing edge to provide an oblique striking surface for air passing through the passages and angularly offset at its meeting edge to direct the air against the said striking surfaces, certain of said fins being hollow and receiving a current of air from the internal bores of the shanks and discharging the same through outlet ports and into the passages between the fins in a manner to augment the flow of air through the said passages.

ANTON ROBER.
